UNITED STATES PATENT OFFICE.

MARION T. WHITNEY, OF CHITWOOD, OREGON.

AUTOMATIC SHADE-ROLLER.

1,057,603.

Specification of Letters Patent. Patented Apr. 1, 1913.

Application filed October 25, 1912. Serial No. 727,819.

To all whom it may concern:

Be it known that I, MARION T. WHITNEY, a citizen of the United States, residing at Chitwood, in the county of Lincoln and 5 State of Oregon, have invented certain new and useful Improvements in Automatic Shade-Rollers; and I do declare the following to be a full, clear, and exact description of the invention, such as will enable others 10 skilled in the art to which it appertains to make and use the same.

This invention relates to improvements in automatic shade rollers.

One object of the invention is to provide 15 an automatic shade roller having an improved means whereby the length of the same may be increased or diminished, thus permitting the roller to be adjusted for use in window frames of different widths.

Another object is to provide an automatic 20 shade roller having means whereby the same may be applied without the use of separate brackets or similar fastening devices, thus permitting the shade to be supported at any 25 desired position in the window frame.

With these and other objects in view, the 30 invention consists of certain novel features of construction, combination and arrangement of parts as will be more fully described and claimed.

In the accompanying drawings: Figure 35 1 is a front view of a portion of a window showing the application of my improved shade roller; Fig. 2 is an enlarged central longitudinal section of the shade roller; Fig. 3 is a cross sectional view taken on the line 3—3 of Fig. 2; Fig. 4 is a similar view 40 through one of the adjustable ends of the shade roller taken on the line 4—4 of Fig. 2. Fig. 5 is a detail perspective view of one of 45 the adjustable end members of the roller and the window frame engaging spring thereof.

Referring more particularly to the drawings 50 1 denotes my improved shade roller which as herein shown is of tubular construction or hollow throughout its entire length. The roller 1 may be formed of any suitable material and has secured to one end a bearing cap or ferrule 3 and to its opposite end a similar cap or ferrule 4. In the 55 ends of the caps or ferrules 3 or 4 are centrally disposed bearing apertures 5 in which

are revolvably mounted the ends of a roller supporting shaft 6 which is disposed in the 55 center of and extends through the roller 1 as shown.

The central portion of the shaft 6 is solid while the ends thereof are tubular as shown. The solid portion of the shaft and the tubular ends thereof may be integral or formed from a single piece of material or as herein shown the tubular ends 7 and 8 may be separate from the solid central portion and secured to the ends of the latter in any suitable 60 manner. The outer extremities of the tubular ends 7 and 8 of the shaft 6 project through the apertures 5 in the caps or ferrules 3 and 4 and thus revolvably support the roller 1. With the extremities of the 70 tubular members 7 and 8 are engaged interiorly threaded sleeves or sockets 9 and 10 having on their outer ends stop plates 11, the diameter of which preferably corresponds to the diameter of the roller as 75 shown. In the threaded sleeve or socket 10 of the right hand end of the roller is screwed an interiorly threaded roller-supporting rod or member 12 having on its outer end a bowed frame-gripping plate 13 which is 80 adapted to be engaged with the inner side of the window frame at this end of the roller.

With the sleeve or socket 9 at the opposite end of the roller is engaged a threaded roller supporting rod or member 14 having on its outer end a bowed frame engaging spring 15 which is adapted to be sprung into engagement with the side of the window frame at this end of the roller and which together with the frame gripping plate 13 will firmly support the roller at any desired 90 position in the window frame. By providing a screw threaded connection between the roller supporting rods 12 and 14 and the 95 sockets 9 and 10 in the ends of the roller supporting shaft 6 it will be seen that the rods or members 12 and 14 may be adjusted or screwed inwardly or outwardly to a sufficient extent to permit the roller to 100 be applied to window frames of different widths as will be readily understood. After the roller supporting rods or members 12 and 14 have been adjusted to the proper position these rods or members are locked 105 by means of jam nuts 16 which are screwed

inwardly thereon against the stop plates 11 on the ends of the sockets 9 and 10 as clearly shown in Fig. 2 of the drawing.

In order to cause the roller to automatically wind the shade after the latter has been unwound therefrom, I provide a coiled roller operating spring 17 which is arranged on one end of the roller supporting shaft 6 and has its inner end securely fastened to 10 said shaft and its outer end securely fastened to the cap 4 on the right hand end of the roller, this end of the spring being preferably secured in an aperture 18 in the end of the cap 4. The spring 17 when 15 thus arranged will be wound up on the end of the shaft 6 when the roller is revolved by the unwinding of the shade, so that when the roller is released the unwinding action of the spring will be imparted there- 20 to to revolve the same in a reverse direction and thereby wind up the shade on the roller. In order to hold the roller against the action of the spring 17 or to prevent the roller from winding up the shade, I pro- 25 vide a pair of pivoted roller-locking gravity pawls 19 which are loosely pivoted at diametrically opposite points to the outer side of the end of the cap 4 and have on their inner edges near their outer ends teeth 20 30 which are adapted to engage suitably formed notches or recesses 21 in the tubular end 8 of the shaft 6 whereby when the roller is revolved by the unwinding of the shade, the pawls will play loosely over the 35 notches or recesses in the end 8 of the shaft and when the shade has been unwound to the desired extent and the revolution of the roller thus stopped one of the pawls will drop into position for engaging its 40 tooth with one of the notches 21 in the end 8 thereby locking or holding the roller against retrograde movement by the spring 17 until the pawl is released by a sudden jerk on and the releasing of the curtain which 45 will permit the spring to revolve the roller in a reverse direction and thus wind up the shade. This pawl and ratchet locking mechanism for the roller may be of the usual or any form of locking mechanism employed 50 in connection with automatic shade rollers for fastening the latter and holding the shade in adjusted position.

By constructing and arranging my improved shade roller as herein shown and de- 55 scribed it will be seen that the same may be readily adjusted and applied to window frames of different widths for supporting a shade roller at any desired position, thus permitting the shade to be hung at the top 60 of the window or part of the way down as may be desired. The improved supporting mechanism for the roller also obviates the necessity of providing brackets or other supporting means. It will also be noted 65 that the roller is of simple and inexpensive

construction and consists of comparatively few parts which are not liable to get out of order.

From the foregoing description taken in connection with the accompanying drawings, the construction and operation of the invention will be readily understood without requiring a more extended explanation. 70

Various changes in the form, proportion and the minor details of construction may be resorted to without departing from the principle or sacrificing any of the advantages of the invention as claimed. 75

Having thus described my invention, what I claim is:

1. A shade roller comprising a hollow body portion, bearing caps arranged on the ends thereof, a supporting shaft arranged in said hollow body portion and having its ends engaged with said bearing caps whereby the roller is revolvably supported, and roller attaching and supporting members having an adjustable engagement with the ends of said shaft whereby the roller may be varied in length for engagement with window frames of different width. 80

2. A shade roller comprising a supporting shaft having tubular ends, a hollow body or shade receiving portion revolvably mounted on said shaft, interiorly threaded sockets engaged with the tubular ends of said shaft, stop plates on the outer ends of said sockets, roller supporting members having a threaded engagement with said sockets whereby said members may be adjusted longitudinally to increase or diminish the length of the roller, means to lock said supporting members in their adjusted positions, a frame gripping plate carried by the outer end of one of said members, a frame engaging spring carried by the outer end of the other supporting member, said gripping plate and frame engaging spring being adapted to be engaged with the sides of a window frame to support the roller at any desired elevation. 90

3. An automatic shade roller comprising a supporting shaft having tubular ends, a hollow shade receiving roller arranged on said shaft, bearing caps secured to the ends of said roller and having therein bearing apertures to receive the ends of said shaft whereby the roller is revolvably supported thereon, interiorly threaded sockets engaged with the tubular ends of said shaft, stop plates arranged on the outer ends of said sockets, roller supporting members arranged in the tubular ends of the shaft and having a threaded engagement with said sockets whereby the members are adjusted to increase or diminish the length of the roller, a frame gripping plate on the outer end of one of said supporting members, a frame gripping spring on the outer end of the other member, jam nuts arranged on said members 100 110 120 130

and adapted to be screwed into engagement with said stop plates to hold the members in their adjusted positions, a coiled spring arranged on and secured at one end to said shaft 5 and having its opposite end secured to one of the caps of the roller whereby when the shade is unwound and the roller thereby revolved the spring will be wound and when the shade and roller are released the 10 winding action of the spring will revolve the roller in an opposite direction to wind

up the shade, and means to automatically lock the roller for holding the shaft in its adjusted position.

In testimony whereof I have hereunto set 15 my hand in presence of two subscribing witnesses.

MARION T. WHITNEY.
